FEEDING MOTOR FOR ROCK DRILLS

William A. Smith, Jr., Cleveland, Ohio, assignor to The Cleveland Rock Drill Company, Cleveland, Ohio, a corporation of Ohio

Application November 27, 1939, Serial No. 306,246

2 Claims. (Cl. 121—9)

This invention relates broadly to rock drills, but more particularly to a feeding mechanism for rock drills of the drifter type.

One object of this invention is to provide a rock drill with a power actuated feeding mechanism capable of imparting feeding motion to the drill in two directions.

Another object of this invention is to provide such feeding mechanism with valve means for automatically shutting off the feeding motor when the rock drill reaches the end of its feeding movement in at least one direction.

Other objects more or less ancillary to the foregoing reside in the specific construction and arrangement of the elements peculiar to this structure, as will become apparent from a more complete examination of this specification.

In the drawings:

Fig. 1 is a side elevational view, partly in section, of a rock drill assembly embodying the invention.

Fig. 2 is an enlarged longitudinal sectional view of the feeding motor shown in Fig. 1.

Fig. 3 is an enlarged cross sectional view taken in a plane indicated by line 3—3 in Fig. 2.

Figs. 4 and 5 are views similar to Fig. 3 illustrating the throttle valve in different positions.

Fig. 6 is an end view of the feeding motor looking in the direction of the arrows 6—6 in Fig. 1.

Fig. 7 is a perspective view of the coupling member shown in Fig. 2.

Fig. 8 is an enlarged cross sectional view taken in a plane indicated by line 8—8 in Fig. 2.

Figs. 9 and 10 are views similar to Fig. 8 illustrating the throttle valve in different positions.

Fig. 11 is a cross sectional view taken in a plane indicated by line 11—11 shown in Fig. 2.

Fig. 12 is a cross sectional view taken in a plane indicated by line 12—12 in Fig. 2.

Fig. 13 is a cross sectional view taken in a plane indicated in line 13—13 in Fig. 2.

Fig. 14 is a cross sectional view taken in a plane indicated in line 14—14 in Fig. 2.

Fig. 15 is a cross sectional view taken in a plane indicated in line 15—15 in Fig. 2.

Referring to the drawings, 20 represents the rock drill assembly including the cylinder 21 having reciprocably mounted therein a piston (not shown) capable of delivering impacts to a drill steel 22 slidably mounted within a front end 23.

On the other end of the cylinder 21, there is mounted a back head 24 held in place by the usual side bolts 25 extending through the cylinder and partly through the front head 23. The rock drill 20 is slidably mounted on a support or shell 26 of substantially U-shaped cross section and provided with the usual conelike member 27 depending therefrom for attachment of the shell on any suitable support. Depending from the cylinder 21, there is a boss 28 slidable within the

shell 26, within which boss is mounted a feed nut 29 held in place by a retaining nut 30. Through the feed nut 29 extends a rotatable feed screw 31 having its left end in Fig. 1, hereinafter referred to as the front end, journaled within a bearing 32 secured to the front end of the shell by one or more bolts 33. The rear end of the shell 26 includes a feed motor housing 34 having its front end closed by a cap 35 and its rear end by a cover 36, the cap 34 being an integral part of the shell 26 while the housing 34 and cover 36 are secured thereto by bolts 37. The rear end of the screw 31 is located in the cap 35 where it is terminated by a head 38 rotatably mounted within a bushing 39 pressed in the front end portion of the cap 35. In the cap 35, there is also the shank 40 of an internal ring gear 41, which shank is journaled within a stationary spacer 40' and is operatively connected to the head 38 of the feed screw 31 by an Oldham coupling 42, thereby permitting slight misalignment of the screw relative to the shank without binding or otherwise increasing the frictional resistance to rotation.

Located in the interior of the ring gear 41, there is the front end portion of a rotor shaft 43, which portion is shaped to form a pinion 44 meshing with three equally spaced gear wheels 45 rotatably mounted on stationary shafts 46 carried by a spider 47 secured to the cap 35 by a dowel pin 48. The gear wheels 45 are also in operative engagement with the internal gear 41 for transmitting rotation thereto from the pinion 44 at a greatly reduced rate of speed. The shaft 43 is journaled within two needle bearings 49 and 103 operatively carried by two longitudinally spaced end plates 50 and 51 respectively, which end plates are also secured to the cap 35 by the dowel pin 48. Clamped between the plates 50 and 51, there is a stator 52 also held against rotation by the dowel pin 48. On its peripheral wall, the stator 52 is provided with a partly circular groove 53 while its interior is shaped to form a rotor chamber 54 of substantially oval shaped cross section within which is rotatably mounted a cylindrical rotor 55 secured on the shaft 43 by a key 56. The rotor closely fits within the chamber 54 at two diametrically opposed places 57 and 58 from which the chamber 54 extends laterally on both sides thereof to form two crescentlike compartments 59 and 60 having their longitudinal ends closed by the plates 50 and 51. The rotor is formed with a plurality of equally spaced longitudinally extending grooves 61 accommodating radially movable vanes 62 capable of fluid tight engagement with the inner wall of the rotor chamber 55, each groove 61 has its bottom wall formed with a small recess 63 extending the full length thereof and consequently opening through the side walls of the

rotor 55, the purpose of which will be explained later.

Formed within the cover 36 of the housing 34, there is a vertical bore 64 accommodating a throttle valve 65 rotatably mounted therein and provided with a handle 66 through which rotation may be imparted to the valve. The bore 64 is closed at its lower end by a plug 67 on which rests a compression spring 68 active on the throttle valve 65 for maintaining it in its uppermost position within the bore 64. Adjacent the handle 66, the throttle valve 65 within the bore 64 is provided with a serrated head 69, the serrations of which are engageable by a spring pressed plunger (not shown) for preventing accidental rotation of the throttle valve. The cover 36 is also formed with a boss 70 having adequately mounted therein a motive fluid connection 71 for admitting motive fluid into the bore 64 through a passage 72. The valve 65 is provided with a central bore 73 and, in the vertical plane indicated by line 3—3 in Fig. 2, with a radial port 74 opening into the bore 73, and with a semicircular groove 75 capable of communication with an exhaust port 76 provided through the wall of the cover 36. In the vertical plane indicated by line 8—8 in Fig. 2, the throttle valve is provided with another radial port 77 opening into the bore 73, and with a semicircular groove 78 capable of communication with an exhaust port 79 also provided through the wall of the cover 36. Radial port 74 is capable of communication with a passageway 80 which leads from the throttle valve through the different parts housed within the housing 34 to open into the rear end portion of a bore 81 provided within the upper front end portion of the cap 35, which bore has slidably mounted therein an auxiliary valve 82 having a shank 83 extending longitudinally from the cap 35 above the feed screw 31 and capable of engagement by the back head 24 of the drill motor 20. This valve is urged and normally maintained in its foremost position within the bore 81 by a compression spring 84 interposed between the valve and the bottom of the bore 81. Longitudinally spaced from the opening of the passageway 80 in the bore 81, there is the opening of another passageway 85 which leads from the bore 81 into the plate 51 via the plate 50 and stator 52. In the plate 50 (Fig. 11) there is provided a port 86 affording communication between the passageway 85 and a niche 87 formed in the side wall of the plate 50 adjacent the stator 52, which niche is capable of communication with the rotor recess 63 shown in the substantially five o'clock position in Figs. 14 and 15. The port 86 extends beyond the niche 87 to finally open through the side wall of the plate 50 adjacent the stator 52 and extends therefrom in the stator 52 to open in the lower portion of the compartment 60 through a recess 88 (Fig. 15). In the stator 52 the passageway 85 is connected with the upper portion of the compartment 59 through a port 90 and a recess 89 (Fig. 15). In the plate 51, the passageway 85 is in communication with a niche 91 through a port 92 (Fig. 13), which niche 91 is capable of communication with the rotor recess 63 shown in the substantially eleven o'clock position in Figs. 14 and 15.

Leading from the throttle valve 65 in the vertical plane indicated by line 8—8 in Fig. 2, there is a passageway 93 opening into a niche 94 (Fig. 13) formed on the face of the plate 13 adjacent the throttle valve 65. From the niche 94 there is a port 95 extending partway through the plate 75

and partway through the stator 52 to end in a recess 96 (Fig. 14) opening into the upper end of the compartment 60. The port 95 is also connected with a niche 97 (Fig. 13) through a port 98, which niche 94 is provided on the side wall of the plate 51 adjacent the stator 52 and is capable of connection with the rotor recess 63 located in the substantially one o'clock position in Figs. 14 and 15. Leading from the niche 94, there is another port 99 which extends in the stator 52 where it is connected with the lower end of the compartment 59 through a recess 100 (Fig. 14). From the stator 52 the port 99 continues into the plate 50 where it is connected with a niche 101 through a port 102 (Fig. 11), which niche is capable of communication with the rotor recess 63 in the substantially seven o'clock position in Figs. 14 and 15.

Disposed at right angle with the lands 57 and 58 engaged by the rotor 55, there is provided through the wall of the stator 52 exhaust ports 104 opening into the partly circular groove 53 of the stator 52, which groove is in constant communication with the atmosphere through an exhaust port 105.

In the operation, when the throttle valve 65 is located as shown in Figs. 3 and 8, it will be understood that since the port 74 is out of communication with the passageway 80 and the port 77 with the passageway 93, admission of the motive fluid through the feed motor 34 is prevented, thereby precluding feeding motion of the rock drill 20 relative to the shell 26. In this instance, the rock drill 20 is secured on the shell 35 against accidental movement relative thereto due to the self-locking threads of the feed screw 31 and feed nut 29. Upon rotation of the throttle valve into the position shown in Figs. 4 and 9, motive fluid from the valve bore 73 (Fig. 9) will flow into the niche 94 through the passageway 93 and therefrom into the recesses 96 and 100 through the ports 95 and 99 respectively, to act on the vanes 61 in the one and seven o'clock position in Fig. 14 for imparting rotation to the rotor 55 in the clockwise direction. After these vanes have uncovered the exhaust ports 104, the motive fluid will exhaust into the annular groove 53 and therefrom to the atmosphere via the exhaust port 105, thereby preventing back pressure on the vanes retarding the rotation of the rotor 55. Concurrently, the vanes subjected to the action of the motive fluid in the compartments 60 and 59 through the recesses 96 and 100 will also be subjected to the action of the motive fluid admitted into the rotor slot 61 through the rotor recesses 63 which are in communication with the niches 97 and 101, the former being supplied with motive fluid through the port 98 communicating with the port 95 (Fig. 13) and the latter through the port 102 (Fig. 11) communicating with the niche 94 through the port 99 (Fig. 13), thereby causing the motive fluid to act on the lower end of the vanes for urging them against the inner wall of the rotor chamber 55.

During the rotation of the rotor 55 in the clockwise direction in Fig. 14, the shaft 54 secured to the rotor by the key 56 will of course transmit rotation in the same direction to the pinion 44 and the gear wheels 45 in the other direction. The wheels 45 operatively engaging the ring gear 47 will transmit rotation thereto in the same direction but at a materially reduced rate of speed, which rotation is finally transmitted to the feed screw 31 through the Oldham coupling 42. Due to the operative en-

gagement of the screw with the feed nut 29, rotation of the feed screw 31 in this last direction will impart forward feeding motion to the rock drill 20 for maintaining the drill steel 22 in contact with the work.

Upon rotation of the throttle valve 65 in the position shown in Figs. 5 and 10, the motive fluid previously admitted into the rotor chamber 55 through the recesses 96 and 100 will now escape therefrom through the passages 95 and 99 respectively, the niche 94, the passageway 93, valve groove 78 and exhaust port 79, as shown in Fig. 10. Concurrently, motive fluid from the throttle valve bore 73 will be admitted into the bore 81 through the passageway 80. With the auxiliary valve 82 in the position shown in Fig. 2, motive fluid from the bore 81 will flow through the passageway 85 into the recess 88 (Fig. 15) through the port 90 and into the recess 88 through the port 86, thereby causing the motive fluid to act on the rotor vanes 62 in the eleven and five o'clock position in Fig. 15 for imparting rotation to the rotor 55 in a counterclockwise direction. Concurrently, from the passageway 85 motive fluid will also be admitted into the niche 91 through the port 92 (Fig. 13) and into the niche 87 (Fig. 11) through the port 86 for admitting motive fluid into the rotor slots 61 through the recesses 63, within which slots are located the vanes 62 acted upon by the motive fluid admitted into the compartments 60 and 59 through the recesses 88 and 89, thereby maintaining these vanes in fluid tight engagement with the inner wall of the rotor chamber 54. As the vanes uncover the exhaust ports 104, the motive fluid will exhaust from the rotor chamber into the semicircular groove 53 and therefrom to the atmosphere via the exhaust port 105.

Rotation of the rotor 55 in a counterclockwise direction in Figs. 14 and 15, will also be transmitted to the pinion 44 through the shaft 43, and from the pinion through the gear wheels 45 to the internal gear 41 in a clockwise direction in Fig. 12, thus resulting in a rotation of the feed screw for imparting rearward feeding motion to the rock drill 20. In this instance, as the rock drill approaches the end of the return or rearward stroke, the head 24 will engage the free end of the valve shank 83 causing the valve to close the passageway 85, thereby automatically shutting off the supply of the motive fluid to the passageway 85 and consequently to the rotor chamber 55 for preventing further operation of the feed motor 34.

Upon rotation of the throttle valve into the position shown in Figs. 4 and 9, the motive fluid previously admitted into the rotor chamber 55 through the recesses 88 and 89 will exhaust therefrom through the passageways 85 and 80, valve groove 75 and exhaust port 76, thereby enabling free rotary movement of the rotor 55 in a clockwise direction as hereinabove explained.

From the foregoing explanation, it will be understood that the fluid motor provided within the housing 34 is of the reversible rotary type equipped with a plurality of inlet ports for admitting motive fluid into the rotor chamber to act on at least two of the vanes 62 carried by the rotor 55, thereby resulting in a powerful rotary motor of simple and efficient construc-

tion. The gears' transmission shown in Fig. 12 are calculated to materially reduce the rotary speed of the motor for transmitting rotation to the feed screw 31 at a greater rate of power than that of the feed motor, a feature which has been found important especially when removing or pulling stuck drill steel from the drilled hole, as well as maintaining the drill steel 22 in contact with the work. By providing the auxiliary valve 82, rearward motion of the drill motor is limited to prevent transmission of impacts by the drilling motor to the housing 34 of the feeding motor. Through the Oldham coupling 42, slight variation of alignment between the feed screw 31 and the gear 41 may take place without resulting in excessive binding or frictional resistance of the several parts of the mechanism.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a fluid actuated rotary motor of the reversible type, a hollow stator, a rotor within said stator, a plurality of vanes operatively carried by said rotor, a pair of diametrically opposed compartments between said stator and rotor of substantially crescent shape cross section, means including a throttle valve for concurrently admitting motive fluid into two diametrically opposed end portions of said compartments and for exhausting motive fluid from the other two opposed end portions thereof for actuating said rotor by virtue of the action of the motive fluid on said vanes, said throttle valve being operable for reversing admission and exhaust of the motive fluid into and from said diametrically opposed end portions for selectively controlling the direction of rotation of said rotor, and an auxiliary valve capable of preventing admission of motive fluid into two diametrically opposed end portions of said compartments irrespective of said throttle valve.

2. In a fluid actuated rotary motor of the reversible type, a stator, a rotor within said stator, a pair of diametrically opposed compartments between said stator and rotor, radially movable vanes carried by said rotor engageable with the outer walls of said compartments, an inlet passage opening into one end of each compartment for concurrently admitting motive fluid to at least two of said blades to effect the rotation of said rotor, a venting passage opening into the other end of each compartment to prevent back pressure therein during said rotation, a rotatable throttle valve associated with said passages for selectively reversing the use thereof to control the direction of rotation of said rotor, a slid valve capable of precluding admission of motive fluid into one end of each compartment irrespective of said throttle valve, and motive fluid exhausting means for each compartment intermediate the ends thereof.

WILLIAM A. SMITH, JR.
